UNITED STATES PATENT OFFICE.

WILLIAM T. BROMWELL, OF ST. LOUIS, MISSOURI.

DESIGN FOR ADVERTISING-DESKS.

Specification forming part of Design No. 7,969, dated January 5, 1875; application filed December 12, 1874.
[Term of Patent 3½ years.]

To all whom it may concern:

Be it known that I, WILLIAM T. BROMWELL, of St. Louis, in the county of St. Louis and State of Missouri, have invented a Design for Advertising-Desks, of which the following is a specification:

The nature of my design is fully represented in the accompanying drawing, to which reference is made.

A represents the body or table portion of the desk, and B is the base part for the frames C, the ornamental design of which forms the subject of this patent. The frame B incloses a series of openings, b. Said openings are surrounded by molding more or less ornamental. Above this series of openings b there is a series of ornate frames, C C C, inclosing openings similar to b b. The frames C C are substantially the same in design, and therefore a description of one will suffice for the whole. The opening in said frame is surmounted by a shield, d, over its central part, and at each side of said shield, and extending therefrom toward the ends of the opening, there is foli-ate scroll e. At each edge of the frame C there is a heavy carved foliate scroll, f, supporting two ribbon-scrolls, g g, which extend across the front of the frame C, and are united at the middle by a small shield. The ribbon-scrolls g g are flanked by foliate carvings h, which support a canopy, i. Beneath the canopy i there is female head in alto-rilievo, surmounted by an arabesque crest, and terminates below by a gorget of drapery. The central frame C is surmounted by the figure of an eagle with expanded wings, though this latter is not essential to the design.

What I claim is—

The ornamental design for the frame C, composed of the shield d, the scrolls e, f, and g, canopy i, supported by the carvings h, and the female head with crest, all substantially as shown and described.
